UNITED STATES PATENT OFFICE.

HENRY R. RANSOM, OF PITTSBURG, KANSAS.

SECURING DEVICE FOR PLATE-GLASS.

No. 818,850.

Specification of Letters Patent.

Patented April 24, 1906.

Application filed December 5, 1905. Serial No. 290,389.

To all whom it may concern:

Be it known that I, HENRY R. RANSOM, a citizen of the United States, residing at Pittsburg, in the county of Crawford and State of Kansas, have invented certain new and useful Improvements in Securing Devices for Plate-Glass; and I do hereby declare the following to be a full, clear, and exact description of the invention, such as will enable others skilled in the art to which it appertains to make and use the same.

My invention relates to means for fastening sections of plate-glass together, and is particularly adapted for assembling the lights of glass constituting show-windows, counters, &c.

The object of the invention is to provide metallic fastening devices which are held in proper relation to one another by means enclosed within the window or case, said devices serving to rigidly fasten the plates of glass either in alinement or at angles to each other and also adapted to connect mullion-plates or partitions to the joints between the plates.

With the above and other objects in view the invention consists of brackets formed of metallic strips so shaped as to overlap the contacting edges of plates of glass and at the same time to receive between them one edge of a partition or mullion plate, said last-mentioned partition or plate being perforated to receive securing means adapted to clamp the brackets upon the partition or plate.

The invention also consists in further novel construction and combination of parts more fully hereinafter described and claimed.

In the accompanying drawings I have shown the preferred form of my invention, and in said drawings—

Figure 1 is a front elevation of portions of two plates connected by means of my improved fastening devices. Fig. 2 is a section on line *x* *x*, Fig. 1. Fig. 3 is a detail view of a portion of one of the plates and showing the manner of beveling the edge thereof to receive one of the brackets. Fig. 4 is a section through plates and the mullion or partition plate disposed at acute angles to each other. Fig. 5 is a detail view showing the formation of the edge of the mullion-plate, and Fig. 6 is a similar view showing the manner of shaping the edge of each of the front plates when disposed in the manner shown in Fig. 4.

Referring to the figures by numerals of reference, 1 1 are glass plates having recesses 2 formed in their abutting edges, the inner

walls of said recesses being beveled, as shown at 3, and the front faces of the plates being slightly recessed, as at 4, so as to receive a hook 5, formed at one end of a metallic strip 6, said hook being so shaped as to fit snugly upon the front face of the plate 1 and upon the beveled wall of the recess 2. Two of these metallic strips are utilized, the hooks 5 thereof being seated within the respective recesses of the plates 1, and when these strips are so located those portions thereof extending backward from the plates lie parallel and are adapted to receive between them one edge of a glass plate 7, constituting a partition or mullion-bar. L-shaped brackets 8 are fitted upon the strips 6 and are adapted to clamp against the inner faces of the plates 1, and when these brackets and the strips 6 are in proper positions they are clamped upon the plate 7 by means of a bolt 9, which extends therethrough and through apertures 10, formed within brackets 8 and strips 6.

A nut 11 is adapted to be screwed on the bolt 9, so as to clamp all these parts together 80 and bind the three plates of glass, so that the same cannot be separated. Where two plates 12 are to be fastened together at an obtuse angle, the abutting edges thereof are grooved, as shown at 13, and these grooves 85 are adapted to receive hooks 14, which fit within the grooves and overlap the outer faces of the plates and are formed at one end of a metallic strip 15. Shoulders 16 are produced between the hooks 14 and the bodies 90 of the strips 15, and these shoulders overlap the inner faces of the plates 12, while the strips 15 are disposed parallel and are adapted to receive between them a glass plate or mullion-bar 17. This plate is adapted to be 95 fastened to the strips 15 by means of a bolt 18, having a nut 19 thereon. Where a plate 17 is used in this manner, the same has its edge preferably beveled in the manner shown in Fig. 5 and provided with grooves 20 to receive the shoulders 16. By utilizing fastening means such as herein described plates of glass can be secured close together and will be firmly held, and as the means for securing the parts are located inside the case or window it will be obvious that it becomes absolutely impossible to detach the plates except from the inside.

It will of course be understood that the joints can be sealed with any suitable cement.

Having thus fully described my invention,

what I claim as new, and desire to secure by Letters Patent, is—

1. The combination with recessed plates contacting at their adjoining edges; of a plate disposed in rear of and overlapping the abutting edges of the recessed plates; parallel metallic strips secured upon opposite faces of the inwardly-extending plate, hooks upon said plates and within the recesses, said hooks contacting and overlapping the outer faces of the recessed plates and means secured to the inwardly-extending plate for holding the recessed plates within the hooks.
2. The combination with plates having abutting edges, said edges having registering recesses therein; of a mullion-plate abutting against and overlapping the edges of the recessed plates, metallic strips secured to opposite faces of the mullion-plate and hooks integral with said strips and disposed within

the recesses, said hooks engaging the recessed plates.

3. The combination with plates having abutting edges, said edges having registering recesses therein; of a mullion-plate in rear of and overlapping the abutting edges of the recessed plates, metallic strips secured to opposite faces of the mullion-plate and overlapping that edge of the mullion-plate contacting with the recessed plates, said strips contacting and seated within the recesses, each strip having an integral hook overlapping the outer face of the recessed plates.

In testimony whereof I have signed my name to this specification in the presence of two subscribing witnesses.

HENRY R. RANSOM.
